UNITED STATES PATENT OFFICE

WILHELM RIEHM, OF AUGSBURG, GERMANY, ASSIGNOR TO MASCHINENFABRIK AUGSBURG-NURNBERG A. G., OF AUGSBURG, GERMANY, A CORPORATION OF GERMANY

TWO-CYCLE ENGINE WITH SLOT SCAVENGING AND AIRLESS FUEL INJECTION

Application filed February 4, 1929, Serial No. 337,255, and in Germany February 17, 1928.

This invention relates to internal combustion engines and more particularly to two cycle engines.

One of the principal objects of the invention is the provision of a two cycle engine operating with airless fuel injection, and having scavenging air and exhaust ports or slots controlled by the piston, means being provided to create a whirling action of the fluid in the combustion chamber substantially at or after the start of the compression stroke. Another object of the invention resides in the method of operation of such an engine.

Other objects and advantages of the invention will be apparent from the following description and the accompanying drawing.

In the drawing, in which like characters of reference designate like parts throughout the several views thereof,

20 Fig. 1 is a longitudinal section through one end of a cylinder embodying the present invention;

Fig. 2 is a transverse section taken at right angles to the cylinder axis along the line 25 A—B of Fig. 1;

Fig. 3 is a section on the line C—D of Fig. 1; and

Fig. 4 is a diagram showing the sequence of operations.

30 This invention is preferably employed in connection with a double acting two stroke engine adapted to operate with airless fuel injection, and is so illustrated in the drawing as one embodiment thereof, although 35 obviously the invention is not to be limited to engines of the double acting type.

For purposes of easier understanding, the drawing is somewhat diagrammatic in form and only so much of the engine is illustrated as is needed for a clear disclosure of the invention. As shown, the engine cylinder α contains two rows of ports or slots b and c , the ports b , being the scavenging ports, are arranged closer to the center of 45 the cylinder than the exhaust or outlet ports c . The entering scavenging stream of air flows in accordance with the arrow shown, when the ports b and c are opened by the piston which controls them, these ports being 50 preferably arranged on one side of the cylinder

55 der in adjacent planes so that the scavenging air flows across the cylinder along the cylinder and then back along the cylinder after reversing itself at the cylinder end, then flowing out of the exhaust slots c , thus effectively scavenging the burnt gas from the combustion chamber.

60 In order to give a rotative or whirling motion to the combustion air, trapped in the cylinder when the piston closes the scavenging slots b , supplementary ports or slots d are provided in the cylinder wall, preferably opposite the slots b and c . The supplementary slots d , like the slots b and c , are adapted to be closed or controlled by the piston, the slots d being preferably arranged 65 in the same transverse plane as the exhaust slots c . A supplementary flow of fluid may pass into the combustion space through these slots d , this fluid being air. As seen from 70 Fig. 2 the slots d are arranged so that the air entering the cylinder is directed substantially tangentially so as to set the fluid in the cylinder into a rotative whirl, and as shown in Fig. 1, the passage e through which 75 the supplementary flow of air passes to the slots d , is inclined upwardly towards the end of the cylinder so that the flow of air entering the cylinder through the ports d is directed at an angle to the cylinder axis. This 80 is in order to prevent a direct flow of air between the slots d and c .

85 In order to avoid a loss of scavenging air and prevent the scavenging air entering through the slots b from immediately escaping through the opposite slots d a suitable means such as a valve f is provided in the passage e , this valve being controlled in any known manner in accordance with the engine operation so as to maintain the passage 90 e closed except when the desired supplementary air flow through the slots or ports d should take place. This valve opens substantially at the time the compression stroke starts, and just after the piston has closed 95 the scavenging air ports b , as indicated at the point 5 in Fig. 4. The valve f controlling the flow of supplementary air through the ports d maintains this passage closed so long as the scavenging air slots b are open, 100

but as soon as the scavenging air slots are closed, as apparent from Fig. 4 of the drawing, see point 3, the valve *f* opens and remains open until after the piston closes the slots *d* and *c*, as indicated at the point 4. The valve lifting curve is shown in section in Fig. 4 as extending from the point 3 to the point 5. The valve *f* is closed after the end of the piston passes by the ports *c* and *d*, while moving towards the head of the cylinder, and the valve *f* remains closed during the uncovering of the slots *c* and *d* on the working or expansion stroke of the piston. The time of opening of the exhaust slot *c* and the supplementary slot *d* is indicated at point 1, while 2 indicates the time of opening of the scavenging slot *b*. U. T. indicates the lower dead center position and O. T. indicates the upper dead center position of the piston.

Any suitable means may be provided for causing a supplementary flow of air through the slots *d* when the passage *e* is opened by the valve *f*, and as this supplementary flow of air is directed substantially tangentially, the contents of the cylinder have a whirling motion imparted to them and are thus caused to move about the axis of the cylinder while the piston moves up towards the head of the cylinder and compresses the contents. The compressed contents of the cylinder are thus whirling when the fuel is introduced through the fuel injection nozzle *g* shown in the cylinder head, and thus an even distribution of the fuel is obtained.

While the method herein described, and the form of apparatus for carrying this method into effect, constitute preferred embodiments of the invention, it is to be understood that the invention is not limited to this precise method and form of apparatus, and that changes may be made in either without departing from the scope of the invention which is defined in the appended claims.

What is claimed is:

1. A two cycle engine of the class described, comprising a cylinder having an exhaust port, a scavenging air inlet port adjacent said exhaust port, and a piston reciprocable within said cylinder to control said ports, said ports being arranged on the cylinder so as to cause a flow of scavenging air across, along, and back along the combustion space, a supplementary port in the cylinder wall at a distance from said exhaust and inlet ports and arranged angularly with respect to radial directions for admitting fluid rotatively to the combustion space substantially at the start of the compression stroke to impart a whirling motion to the fluid in the cylinder.

2. A two cycle engine of the class described operating with airless fuel injection, comprising a cylinder having an exhaust port, a scavenging air inlet port, and a piston

reciprocable within said cylinder to control said ports, said ports being arranged on the cylinder at one side thereof in adjacent parallel planes so as to cause a flow of scavenging air across, along, and back along the combustion space, and a supplementary port in the cylinder wall arranged angularly with respect to radial directions and at a distance from said inlet and exhaust ports for admitting fluid rotatively to the combustion space to impart a whirling motion to the fluid in the cylinder, said supplementary port being positioned at such a location in the cylinder wall as to be controlled by the piston substantially simultaneously with the control of said exhaust port, and a valve for controlling the flow through said supplementary port and mechanism for operating said valve to open it after the piston has uncovered the said inlet ports.

3. A two cycle engine of the class described, operating with airless fuel injection, comprising a cylinder having exhaust ports, scavenging air inlet ports, and a piston reciprocable within said cylinder to control said ports, said ports being arranged on one side of the cylinder to provide for reversed scavenging flow, and supplementary air inlet ports independent of said scavenging air inlet ports provided in said cylinder opposite said scavenging and exhaust ports and adapted to be closed by said piston substantially concurrently with the closing of said exhaust ports, said supplementary ports being arranged at an angle to the radial directions so that the air flows therethrough in a substantially tangentially direction to set the fluid in the cylinder into a rotative whirl.

4. A two cycle engine of the class described, operating with airless fuel injection, comprising a cylinder having exhaust ports, scavenging air inlet ports, and a piston reciprocable within said cylinder to control said ports, said ports being arranged on one side of the cylinder to provide for reversed scavenging flow, and supplementary air inlet ports independent of said scavenging air inlet ports provided in said cylinder opposite said scavenging and exhaust ports and adapted to be closed by said piston substantially concurrently with the closing of said exhaust ports, said supplementary ports being arranged so that the air flows therethrough in a substantially tangentially direction and inclined transversely toward the end of the cylinder to set the fluid in the cylinder into a rotative whirl.

5. A two cycle engine of the class described, operating with airless fuel injection, comprising a cylinder having exhaust ports, scavenging air inlet ports, and a piston reciprocable within said cylinder to control said ports, said ports being arranged on one side of the cylinder to provide for reversed scavenging flow, and supplementary air inlet

ports independent of said scavenging air inlet ports provided in said cylinder opposite said scavenging and exhaust ports and adapted to be closed by said piston substantially concurrently with the closing of said exhaust ports, said supplementary ports being arranged so that the air flows therethrough in a substantially tangentially direction to set the fluid in the cylinder into a rotative whirl, and a valve for controlling the flow of supplementary air through said supplementary ports and adapted to open substantially at the time of closing of the scavenging air inlet ports.

15 In testimony whereof I have affixed my signature.

WILHELM RIEHM.
